UNITED STATES PATENT OFFICE.

WARD S. IRELAND, OF DALLAS, TEXAS.

TYPE-WRITING MACHINE.

980,275

Specification of Letters Patent. Patented Jan. 3, 1911.

Application filed April 5, 1910. Serial No. 553,497.

To all whom it may concern:

Be it known that I, WARD S. IRELAND, of Dallas, in the county of Dallas and State of Texas, have invented certain new and useful

5 Improvements in Type-Writing Machines; and I do hereby declare the following to be a full, clear, and exact description of the invention, such as will enable others skilled in the art to which it appertains to make and 10 use the same.

This invention relates to improvements in typewriting machines and more particularly to improved rewinding mechanism for the paper,—the object of the invention being to 15 so construct a rewinding mechanism that the amount of paper rewound will not exceed the amount of paper fed forward, at each manipulation of the key mechanism, notwithstanding the gradually increasing diameter of the roll of rewound paper.

20 With this object in view the invention consists in certain novel features of construction and combinations of parts as will hereinafter be set forth and pointed out in the 25 claims.

In the accompanying drawings, Figure 1 is a sectional view of a typewriting machine showing my improved rewinding mechanism in side elevation, and Fig. 2 is a plan view, 30 partly in section, with the main frame of the machine and key mechanism omitted.

1 represents a portion of the frame of a typewriting machine in which key-bars 2 are mounted and provided with upwardly 35 projecting arms 3. The arm 3 of each key-lever is loosely connected at its upper end with the lower end of a type-bar 4,—the latter being pivotally supported between its ends and provided at its upper end with a 40 proper type. A platen bar 5 is disposed in position to coöperate with the type at the upper ends of the type-bars and this platen bar is provided with arms 6 which are pivotally supported by a rod or shaft 7 and the 45 rear ends of said arms are disposed under a fixed bar 8. An inking ribbon 9 passes between the faces of the type and the platen bar 5 and between the latter and the inking ribbon, the sheet or strip of paper 10 to be 50 printed upon is passed.

A supply roll 11 of paper is suitably supported as indicated at 12 and the paper from this roll passes upwardly between the platen bar and the inking ribbon and then in a direction toward the rear of the machine. After 55 passing over a feed roller 12 mounted on

the shaft 7, the paper passes beyond the rear end of the machine and is finally wound upon a reel 13 which is mounted and operated in a manner hereinafter explained. 60

Two arms or brackets 14—15 are secured to the frame of the machine and extend a distance beyond the rear end of the latter. The arm 15 supports, at its free end, a stub-shaft or journal 17 on which a disk 18 is 65 loosely mounted and pressed in a direction toward the inner end of said stub-shaft or journal by means of a spring 19,—the said disk being provided on its inner face with a series of small projections 20 to enter sockets 70 in one head of the reel 13. The other head of this reel is similarly connected with a disk 21 carried by a stub-shaft or journal 22 mounted in the hub 23 of a pinion 24. The hub 23 is mounted in a bearing afforded 75 therefor at the free end of the arm or bracket 14 and is movable longitudinally in said bearing, being held in the position to which it may be moved by means of a set screw 25 entering one of two grooves 26 in 80 the hub 23. When it is desired to remove the reel 13, this can be readily accomplished by first pressing the reel laterally against the resistance of the spring 19 and then withdrawing it from between the holding disks 85 18 and 21. A stub-shaft 27 is mounted in a suitable bearing on the arm or bracket 14 and carries a gear wheel 28 and a crank-arm 29. Normally during the operation of the machine, the gearing will be disposed as 90 shown in Fig. 2, but when it is desired to rotate the reel 13 manually, the pinion 24 will be moved in a direction to cause it to mesh with the gear wheel 28 and then, by turning the latter with the use of the crank-arm 29, motion will be imparted to the reel for rotating it. As above stated however, this gearing will be normally out of mesh as 95 shown in Fig. 2, during the rewinding of the paper strip or sheet when the machine is in 100 operation.

Levers 30 are loosely mounted between their ends upon the rod or shaft 7 near respective arms 6 of the platen bar 5 and to the lower ends of the depending arms of 105 these levers, rods or pitmen 31 are connected. The other ends of these rods or pitmen 31 are supported by means of links 32 mounted loosely on and depending from the fulcrum rod 33 on which the type-bars 4 are hung. 110 The rods or pitmen 31 project beyond the vertical plane of the type-bars and are con-

nected with the ends of a rod 34 disposed in position to be moved when one or more of the type-bars may be operated.

The upwardly extending arms of the levers 30 are connected with a rod or bar 35 disposed over the feed roller 12 and this rod or bar carries a feeder 36 which cooperates with the roller 12 to feed the paper at each manipulation of the keys. Also attached to or connected with the upper ends of the levers 30 are two rods or bars 37 which are supported by means of diagonally disposed links 38 attached at their lower ends to intermediate portions of said rods or bars and at their upper ends to the brackets 14 and 15. Arms 39 are pivotally connected with the free ends of the rods or bars 37, said arms being curved downwardly and extending in a direction toward the rear of the machine frame where they are attached to a rod or bar preferably in the form of roller 40 adapted to rest upon the sheet or strip of paper 10 after the latter has passed the feed roller 12. One of the pivoted arms 39 is provided with an extension 41 having a blunt-ended tooth 42 at its free end to engage a ratchet wheel 43 secured to the stub-shaft 22.

When a key-lever is operated, the lower arm of the type-bar or lever will move the rod 34 forwardly and thus transmit motion, through the medium of the pitmen 31 to the levers 30. This will cause the rods or bars 37 to move in a direction toward the reel 13 and the tooth 42 to coöperate with the ratchet wheel 43 and turn the reel 13 sufficiently to wind an amount of paper approximately equal to the amount of paper moved forwardly by the feeding mechanism of the machine. It will be observed that the roller 40 carried by the arms 39 will rest upon the paper sheet or strip with sufficient pressure to depress the same and cause it to assume a position such as illustrated in Fig. 1 when the rewinding mechanism is first started and there is but a small amount of paper on the reel. When the parts are operated as above described, the rods or bars 37 will not only move longitudinally but, by reason of the inclined links 38, said bars will be caused to rise slightly and raise the arms 39,—thus relieving somewhat the pressure of the roller 40 upon the paper and permitting the latter to slacken. On account of this operation, the reel will be caused to wind slackened paper thereupon and thus reduce to a minimum the possibility of winding more paper upon the reel than has been permitted to be fed forwardly by the feeding mechanism when the machine is operated to print. As the paper accumulates on the reel and the roll of paper thus increases in diameter, there may be a greater pulling force exerted on the paper sheet and more paper might be

wound on the reel than had been fed forward by the paper feed mechanism of the machine. It will be observed however, that when that portion of the paper strip or sheet between the feed roller 12 and the reel tends to become taut, the arms 39 will be raised and the tooth 42 moved in a direction away from the teeth of the ratchet wheel 43. If this movement is very slight, the tooth 42 may engage but slightly a tooth of the ratchet wheel 43 and then slip off, thereby turning the reel a short distance only. Should the paper strip become suddenly tight from any cause, the arms 39 may be raised sufficiently to completely disengage the tooth 42 from the ratchet wheel 43 and thus no movement of the reel 13 would be effected should the machine be operated at this time. It is apparent that during the operation of the rewinding mechanism, the tooth 42 may be caused automatically by the condition of the paper, to coöperate with the ratchet wheel 43 in an intermitting manner and in this way prevent the reel 13 from being turned, under any conditions, far enough to pull papers through the paper feed mechanism of the machine.

In order to prevent retrograde movement of the reel 13, a weighted dog 44 to co-operate with the ratchet wheel 43 may be employed.

Having fully described my invention what I claim as new and desire to secure by Letters-Patent, is,—

1. In mechanism of the character described, the combination with a reel and a ratchet wheel movable therewith, of a longitudinally movable bar, an arm pivotally supported by said bar and adapted to co-operate with a strip or sheet of paper to be reeled, and a tooth movable with said pivoted arm and longitudinally movable bar and adapted to coöperate with said ratchet wheel.

2. In a mechanism of the character described, the combination with a ratchet wheel and means for connecting the same with a reel, of a longitudinally movable bar, and an arm pivotally supported by said bar and provided with a tooth to coöperate with said ratchet wheel, said arm disposed in position to be actuated by paper to be reeled and move the dog relatively to the ratchet wheel.

3. In mechanism of the character described, the combination with a ratchet wheel, means for supporting the same, and means for connecting said ratchet wheel with a reel, of a longitudinally movable bar, a pivoted arm carried by said bar and adapted to be supported at its free end by the paper to be reeled, and a tooth or dog carried by said pivoted arm for coöperation with said ratchet wheel.

4. In mechanism of the character de-

scribed, the combination with a ratchet wheel, means for supporting the same, and means for connecting said ratchet wheel with a reel, of a longitudinally movable bar, an arm pivoted to one end of said bar and adapted to be supported at its other end by the paper to be reeled, a tooth carried by said pivoted arm for coöperation with the ratchet wheel, and means for raising said bar and 10 pivoted arm when the bar is moved longitudinally in one direction.

5. In mechanism of the character described, the combination with a bracket, a ratchet wheel supported thereby, and means 15 for connecting a reel with said ratchet wheel, of a longitudinally movable bar, a link pivotally attached to said bracket and connected with said longitudinally movable bar, an arm pivotally connected at one end with the 20 longitudinally movable bar and adapted at its other end to be supported by paper to be reeled, and a tooth or dog carried by said pivoted arm for coöperation with the ratchet wheel.

25 6. In mechanism of the character described, the combination with a bracket, of a ratchet wheel supported thereby, means for connecting a reel with said ratchet wheel, a lever pivotally supported between its ends, 30 means for oscillating said lever, a longitudinally movable bar pivoted at one end to an arm of said lever, a pivoted link connecting said bar with the bracket, an arm pivotally attached to the free end of said bar and 35 adapted at its other end to coöperate with the paper to be reeled, and a tooth carried by said pivoted arm for coöperation with the ratchet wheel.

7. In mechanism of the character described, the combination with two brackets, means at the free ends of said brackets for supporting a reel, and a ratchet wheel adapted for connection with said reel, of two longitudinally movable bars, pivoted links connecting said bars and brackets, arms pivotally attached to the free ends of said bars, a rod or roller connecting the free ends of

said pivoted arms and adapted to rest on paper to be reeled, a tooth carried by one of said pivoted arms for coöperation with the 50 ratchet wheel, and means for reciprocating said longitudinally movable bar.

8. In rewinding mechanism for type-writing machines, the combination with the machine frame and brackets secured thereto, 55 of means on said brackets for supporting a reel, a ratchet wheel for turning said reel, levers pivotally supported between their ends in the machine frame, longitudinally movable bars connected with the upper arms of said 60 levers and supported by the brackets, arms pivoted to said longitudinally movable bars, a member connecting the free ends of said pivoted arms and adapted to rest upon paper to be wound on the reel, a tooth or dog carried by one of said pivoted arms for coöperation with the ratchet wheel to turn the 65 reel, pitmen connected at one end with the depending arms of said levers, links supporting the other ends of said pitmen, and a 70 rod connecting said pitmen and disposed in position to be actuated by the writing mechanism of the machine.

9. In a rewinding mechanism, the combination with reel supporting means and mechanism for actuating said reel supporting means intermittently, of a gear wheel, means for operating the gear wheel manually, a pinion having a hub movable longitudinally by the reel supporting means, means for holding said pinion normally out of mesh with said gear wheel when the intermitting rewinding mechanism is to be operated and for holding said pinion in mesh with the gear wheel when the latter is to be operated 85 to turn the reel manually.

In testimony whereof, I have signed this specification in the presence of two subscribing witnesses.
